UNITED STATES PATENT OFFICE.

WILLIAM W. BRILHART, OF INDIANA, PENNSYLVANIA.

SPECTACLE-CASE.

SPECIFICATION forming part of Letters Patent No. 410,234, dated September 3, 1889.

Application filed December 3, 1888. Serial No. 292,479. (No model.)

To all whom it may concern:

Be it known that I, WILLIAM W. BRILHART, a citizen of the United States, and a resident of Indiana, in the county of Indiana and State 5 of Pennsylvania, have invented certain new and useful Improvements in Spectacle-Cases; and I do declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 Figure 1 of the drawings is a representation of this invention and is a cross-section. Fig. 2 is a plan view showing one side. Fig. 3 is a section taken lengthwise of the case.

This invention has relation to improvements 20 in spectacle-cases; and it consists in the construction and novel combination of parts, as hereinafter set forth.

Two pairs of spectacles are often required by a person, one pair for reading and the 25 other for seeing at a distance; but objection is found to the two pairs, as two cases are required, which ordinarily take up too much room in the pocket. To obviate this difficulty I provide the present invention, wherein two 30 pairs of spectacles may be accommodated in one case, occupying no greater room in the pocket than the single case of ordinary manufacture.

Referring to the drawings, A designates the 35 outer shell or casing, which may be of any

suitable material; and B is a longitudinal partition of thin material secured within and dividing the shell into two receptacles C. The shell on each side has the central longitudinal swell D to accommodate the bows of the spectacles, and the depressed portions E at the sides of the swell are designed to fit closely down to the frame of the spectacles. By this formation the case requires but little room in the pocket. The partition B, being a 40 single sheet of thin metal or other suitable material, takes but very little space in the shell and should have its end projecting above the open end of the case, as shown, and a soft lining a may be secured to the two sides of 45 the partition to protect the glasses. The sides of the shell may be differently colored, and one side may be provided with a small protuberance, usually slotted, and provided with a catch or pin v, for attachment to the lining 50 of the pocket.

Having described my invention, what I claim is—

In a spectacle-case, the shell having the longitudinal swell portions, the depressed portions at the sides thereof, and the longitudinal partition having the soft lining and having the extended end, substantially as specified. 60

In testimony whereof I affix my signature in 65 presence of two witnesses.

WILLIAM W. BRILHART.
